SIGNAL GENERATOR

William R. Flatford, Bartlesville, Okla., assignor
to Phillips Petroleum Company, a corporation
of Delaware

Application September 9, 1944, Serial No. 553,337

4 Claims. (Cl. 175—373)

1

This invention relates to signal generators of a type especially adapted for use in the electrical logging of oil wells and the like while drilling, and is further of the type which is a self-contained source of suitable signal current which can be lowered into the bore hole with the drilling bit.

An object of this invention is to provide a combined signal generator and time control mechanism therefor by means of which current from a direct current source such as dry batteries is converted by means of a vibrator-converter into a low frequency alternating current having a frequency of the order of 8 to 10 cycles per second, a square wave form, and a relatively high current value of the order of 6 amperes.

A further object of this invention is to provide a compact, rugged unit so constructed that the signal generated thereby will not be affected by the rotation of the bit or other vibrations due to drilling.

Other and more detailed objects of the invention will be apparent from the following disclosure of the embodiment thereof illustrated in the attached drawings.

This invention resides substantially in the combination, construction, arrangement and relative location of parts, all as will be described in detail below.

In the accompanying drawings,

Figure 1 is a vertical, central, cross-sectional view through the vibrator-converter portion of the device;

Figure 2 is a cross-sectional view taken on the line 2—2 of Figure 1;

Figure 3 is a cross-sectional view taken on the line 3—3 of Figure 1;

Figure 4 is an elevational view of another portion of the unit showing pole pieces in cross-section, which unit portion is adapted to be mounted on the upper end of the unit portion of Figure 1;

Figure 4A is a side elevational detailed view of a pair of brackets forming part of the structure of Figure 4;

Figure 4B is a side elevational view of one of said brackets;

Figure 4C is a top plan view of these brackets shown in their relative assembled position;

Figure 5 is a cross-sectional view taken on the line 5—5 of Figure 4;

Figure 6 is a cross-sectional view taken on the line 6—6 of Figure 4;

Figure 7 is a cross-sectional view taken on the line 7—7 of Figure 4;

2

Figure 7A is a side elevational view of the upper terminal element of the structure of Figure 4;

Figure 7B is a similar view from a right angle position with respect to Figure 7A;

Figure 7C is a top plan view of this element;

Figure 7D is a bottom plan view thereof;

Figure 8 is a vertical, central, cross-sectional view through the time control portion of the unit showing some parts in elevation, which unit portion is adapted to be mounted on the upper end of the unit portion of Figure 4;

Figure 9 is a cross-sectional view taken on the line 9—9 of Figure 8;

Figure 10 is a cross-sectional view taken on the line 10—10 of Figure 8;

Figure 11 is a cross-sectional view taken on the line 11—11 of Figure 8;

Figure 11A shows the parts of Figure 11 in switch open position;

Figure 12 is a cross-sectional view taken on the line 12—12 of Figure 8;

Figure 12A is a cross-sectional view taken on the line 12A—12A of Figure 8; and

Figure 13 is a circuit diagram of the electrical connections of the device.

The function of the various parts of the device of this invention will be best understood after a detailed disclosure of the structure of which it is composed, and its description will, therefore be deferred until later.

Referring to Figures 1, 2 and 3, the unit portion illustrated therein comprising the vibrator-converter includes a cylindrical housing 1, preferably of metal, closed at the lower end, and of a size which will permit of its introduction into a bore hole, as for example an overall diameter of two inches. The housing 1 is attached to a non-magnetic structure 3 which is provided with a seat therefor, as shown. The element 3 is of brass or other non-magnetic material and serves as a mount for the bearing 12 of shaft 13 (see Fig. 3) and has a seat on its upper end for housing section 6 of non-magnetic material such as brass. The housing 6 serves as an enclosure or container for coil form 2 and winding 14, as clearly shown in Figure 1. At 3' are a pair of magnetizable pole pieces which have the outline clearly shown in Figure 1. These pole pieces are mounted in slots in the non-magnetic element 3 as shown in Figure 3. The housing 6 is in fact, as shown in Figure 2, made up of two nearly semi-circular halves which together with the magnetizable strips or bars 6' complete the circular housing. The magnetizable strips 6' seat in corner notches in the pole pieces 3', as clearly shown

50
55

in Figure 1, and extend all the way to the top of the casing 6 of which they form a part, also as shown in Figure 1. When the unit of Figure 4 is mounted on the top of the housing 6 the magnetizable strips 6' will abut the pole pieces 15 of Figure 4. The upper portion of the structure 2 is tubular in form and provides a coil form for the magnetizable winding 14. A magnetizable armature 10 is pivotally mounted at 11 in the structure 3 by means of ball bearings 12, from which it is insulated by means of the insulating sleeves 13. The supporting shaft 11 is connected by a resilient pigtail 19 to a terminal block 4, as shown in Figure 3, to which one end of the winding 14 is connected as well as a wire 31 to be described later. The other end of the winding 14 is connected to wire 5 which has a branch connection 32 for a purpose to be described later. As will be described later in connection with Figure 13, wire 5 extends to the battery source (not shown). Any type of battery case or container can be suspended or attached by any suitable means to the bottom of unit 1 (see Fig. 1) as indicated by the dotted extension lines B. This case or container forms a housing for batteries 17 and 22 connected as shown in Figure 13 to wires 5, 5^a, 5^b, 7 and 8. Mounted in the upper end of the magnet tube 2 is a copper ring 20 employed for the purpose of making the action of the magnet 2-14 sluggish.

Mounted on the lower end of the armature 10 and in electrical contact therewith are a pair of spring arms each supporting one of a pair of contacts 18, the other of which is mounted on an insulating block on the inner wall of the tube 1. A fixed contact of each contact pair 18 is connected by the wires 5^a and 5^b respectively to the current source as will be described in connection with Figure 13. Also mounted upon the armature 10 and in electrical contact therewith is another pair of spring arms carrying a contact of each of the pairs 21. The other contact of each pair is mounted upon a spring arm 21A which is mounted upon the same insulating block which supports a fixed contact of the contact pairs 18. These blocks have adjusting screws 26 for placing the springs 21A under tension by reason of the fact that their lower ends engage insulating stops near the bottom of tube 1, as shown. The spring fingers 21A are connected by the wires 7 and 8 respectively to the signal current source 22, as will be explained in connection with Figure 13. The lower end of the armature 10 has an aperture therethrough as shown, in which a frictional damping piston 25 is slidably mounted and connected to the spring fingers which support one contact of each of the contact pairs 21. The tensioning of the spring fingers 21A and the damping piston 25 serve to prevent bouncing or sharp reactions of the armature by reason of the engagement and disengagement of the contacts of contact pairs 21. The upper end of the armature 10 oscillates on the shaft 11 within the tubular magnet core 2.

In Figures 4 to 7 inclusive is illustrated the next unit portion of the device. This unit portion comprises an attaching member forming an extension of the coil form 2 and the housing 6. This extension comprises a pair of members 15^a and 15^b made of some non-magnetic material such as brass. The pole pieces 15 are set between these two members 15^a and 15^b which are nearly semi-circular so as to form together as illustrated in Figure 5, a disc the parts of which can be secured together in any suitable manner. The di-

ameter of this disc unit is equal to the external diameter of the housing 6 and is provided with a pair of holes 15^c by means of which the disc can be attached to the end of the coil form by means of screws. The disc unit is provided with another pair of holes 15^c by means of which a pair of brackets S (See Figs. 4 and 4A to 4C) are mounted thereon. Thus the holes 15^c and the brackets S will line up with the holes 15^c and the brackets 10 secured by screws therein. The upper ends of the brackets are attached by means of screws in the holes 15^c to a notched disc 6^b (see Figs. 4 and 6), on which the upper portion of this part of the unit is mounted. Clamped between the brackets 15 S by means of screws or bolts in the holes 15^c are a pair of semi-circular permanent magnets 16 and 27, the former of which contacts the pole pieces 15. Set in radial slots in the non-magnetic disc 6^b are a pair of magnetizable extensions 28' of the magnetizable member 28 shown in full detail in Figures 7A to 7D. These extensions 28' contact the ends of the permanent magnet 27 so that the member 28 forms part of the magnetic circuit thereof. The member 28 is ring-like, as 20 shown, with the integral extensions 28' extending in one direction and an extension 28'' of reduced diameter extending in the opposite direction to receive an enclosing ring 28^a which is sweated onto the member 28 and forms a continuation of 25 the full diameter of the device and a seat for the 30 attachment thereto of unit 9 as indicated by the unit 9 of Figure 8, as indicated by the broken lines 9 in Figure 4.

As clearly shown in Figures 7 to 7C the interior 35 of the member 28 is shaped to form a substantially rectangular enclosure in which a magnetizing winding 29 is mounted. The terminals of this winding are connected to the wires 31 and 32 respectively of Figure 1, and hence the winding 29 40 is in parallel with the winding 14 (see Fig. 13). An armature 30 is pivotally mounted on one of the screws 33 which passes through one of the apertures 6^a by means of which the disc 6^b is attached to the upper ends of the brackets S. The 45 Magnetizable member 28 has a radial slot at 28^b in which the end of the armature oscillates and on which end a vertical extension 34 is attached. This extension is provided with a spring finger 36 at its upper end.

50 Spring finger 36 extends upwardly into the unit portion illustrated in Figure 8 comprising a tubular housing 9 of any suitable material but preferably of metal and comprising a pair of telescoped tubes, as shown. This cylinder is closed at the 55 upper end as illustrated in Figure 8. At this point it may be well to note that the unit section of Figure 4 is placed on the upper end of the unit section of Figure 1, and the unit section of Figure 8 is placed on the upper end of the unit section of Figure 4. These parts are secured together in any suitable manner to form a single elongated structure of uniform external diameter and adapted to be lowered into a bore hole. Within the housing 9 are a spaced pair of supports 50 and 51 in which are journaled at the 60 ends a pair of threaded shafts 41 and 42 on which are respectively mounted the internally threaded pinions 39 and 40. Likewise journaled between supports 50 and 51 is a long pinion 38 positioned 65 between the threaded shafts 41 and 42 so as to mesh with the pinions 39 and 40, as is clear from Figure 9.

70 On the lower end of the gear 38 is a gear 37 positioned to be engaged by the spring finger 36, 75 and by a fixed pawl 35 which prevents any back-

lashing in the movement of this gear. Mounted on the support 51 is an insulating support 52 through which the threaded shafts 41 and 42 extend but their extensions have reduced diameters, as shown. Indeed these extensions pass through to the top of the instrument as is clear from Figure 8. However, shaft 42 has an enlarged portion 53 just above the support 52 and which is notched out as indicated at 54, in which the tail of a pivotally mounted spring pressed latch 55 engages. The spring acts to urge the latch 55 in a counterclockwise direction, Figure 11A. The other end of the latch is adapted to engage a pivotally mounted insulating arm 56 which in turn bears upon a spring finger 57 mounted upon the insulating support 52. This spring finger is connected to the wire 31 as shown. This spring finger has a contact on it adapted to cooperate with a fixed contact 58 mounted on the support 52, which is connected by the wire 59, see Figures 8 and 13, to another switch to be described.

Mounted in the housing 9 is another support 60, preferably of insulating material above which an escape mechanism is mounted. This mechanism includes a pair of arms 61 and 62 pivotally mounted on the support 63. These arms are united at their free ends by a tension spring 64. As will be seen from Figure 8, the arms 61 and 62 have lateral extensions at different levels for cooperation with the cams 65 and 66 respectively. These cams are mounted upon the shaft 41 and are rotated by it. Rotatably mounted upon the shaft above these cams is a pawl 67 which is connected to the shaft by means of a spring 68 encircling the shaft. The pawl 67 cooperates with the oppositely facing shoulders 69 and 70 on the upper faces of the arms 61 and 62 respectively. In Figure 12A, shoulder 69 faces downwardly and shoulder 70 faces upwardly. Secured to the hub 71 of the pawl 67 is an eccentric cam 72 upon which a crank arm 73 is mounted. This crank arm is pivotally connected at 74 to a switch arm 75 pivotally mounted on the support 60 at 76. This switch arm is provided at the end with a contact which cooperates with a fixed contact 77 connected to the wire 59. A switch arm 75 is grounded on the housing if it is of metal by means of a spring contact 78.

The circuit connections have been indicated briefly in the previous description, but they are clearly shown in Figure 13. The operating battery 17 for the windings 14 and 29 comprises a pair of sections having a center connection to the wire 5 so that these magnets can be alternately energized in opposite directions as the armature 10 oscillates to make and break circuits from these batteries at the contacts 18. Thus in the position of the parts shown current will flow from the left hand portion of battery 17 through wire 5, through coil 14, pigtail 19, armature 10, contacts 18 and wire 5 back to the battery. This will energize the winding 14 in view of its polarization by the permanent magnet 16 so as to cause the armature to move from the position shown in counterclockwise direction to its other position where the right hand contacts 18 make. Those skilled in the art can readily trace the circuit thus made to effect reverse energization of the winding 14 through the other portion of the battery 17 to cause the armature 10 to move back to the position shown in Figure 13. The short circuited copper ring 20 illustrated in Figure 1 will delay the building up of the magnetic field of the magnet 14 to cause the desired slow oscillation of the

armature 10 and the generation of a low frequency current, as will now be described. It is, of course, apparent that the inertia of the oscillating armature 10 can be adjusted to contribute to the desired speed of operation.

As previously stated the winding 29 is in parallel with the winding 14 so that it too is simultaneously energized in alternate directions which due to its polarization by the permanent magnet 27 will cause an oscillation of the armature 30 at the same frequency, thereby driving the mechanism of the unit portion of Figure 8 through the spring finger 36 in a manner shortly to be described.

The oscillation of the armature 10 will convert the direct current from the battery source 22 into a low frequency alternating current of substantially square wave form by reason of the fact that circuits are alternately completed as follows: Current flows from ground through the right hand portion of the battery 22, right hand contacts 21, armature 10, pigtail 19, wire 31, and switches 23 and 24 when closed to ground. When the armature shifts to its other position this same circuit will be completed from the other portion of the battery 22 through the left hand pair of contacts 21. The alternate making and breaking of the contact pairs 21 will produce an alternating current of square wave form of a frequency corresponding to the frequency of oscillation of the armature 10 in a manner well known to those skilled in the art.

This signal current, however, is not generated except when switches 23 and 24 are closed. The mechanical mechanism for operating these switches will now be described. As the device is ready to be loaded into the bore hole the circuit from the battery 17 to the winding 14 is closed in any suitable manner, as by means of a switch, not shown, so as to set the armature 10 in oscillation. Winding 29 being in parallel with the winding 14 is intermittently energized at the same time, causing armature 30 to oscillate back and forth on its pivot support 33. Thus the spring finger 36 moves back and forth to cause intermittent rotation of the ratchet wheel 37 and rotation with it of the elongated gear 38. The rotation of gear 38 causes rotation of the gears 39 and 40 on the threaded shafts 41 and 42. Since the gears 39 and 40 are threadedly mounted on these shafts they simply rotate and slowly travel up the shafts 41 and 42. Their rate of travel can be predetermined for any speed of oscillation of the armature 10 and hence the armature 30 by the proper selection of ratio of gear 38 to the gears 39 and 40. Likewise the speed of vertical movement of the gears 39 and 40 on the threaded shafts 41 and 42 can be predetermined by the proper selection of thread sizes. When gear 40 reaches the end of the thread at the upper end of shaft 42, continued rotation of gear 38, and hence gear 40, will cause rotation of threaded shaft 42 because the threaded gear 40 jams on that shaft.

When the shaft 42 rotates from the position shown in Figure 11A to about the position shown in Figure 11, the notched portion 53 thereof will release the pawl of the spring pressed trigger 55 so that it moves to the position shown in Figure 11, and moves the arm 56 in a counter-clockwise direction to close switch 23 as shown in Figure 11. These parts are all proportioned so that the operator will have sufficient time to drop the generator in the bore hole or the drill bit with the generator attached to the bottom of the bore hole. Threaded gear 39 reaches the end of the threads

on the shaft 41 at about the same time so that it jams thereon and starts rotation of the shaft 41, and hence the cams 65 and 66. These cams respectively engage the lateral shoulders on the pivotally supported arms 61 and 62 so as to alternately move them outwardly. Assuming that the parts are in the position shown in Figure 12, when cam 65 moves arm 61 outwardly, Figure 12A, its shoulder 69 will disengage the pawl 67, permitting spring 68 which is loaded to snap the pawl around through an angle of approximately 180 degrees until the pawl engages the shoulder 70 on the arm 62. This rotation of pawl 67 causes rotation of the eccentric 72 and the movement of crank arm 73, so as to open or close switch 24, depending upon the position it is in. It is preferred that at the start of operations switch 24 be in closed position, as shown in Figure 12A, so that the first movement of the eccentric 72 will open the switch 24. Thus when switch 23 closes, switch 24 already being closed, the alternating current output of the signal generator will be applied to the drill pipe through the connection 100, Figure 13, which is grounded on the drill pipe, as indicated. Thus the alternating current output of the generator will be applied at one terminal to the drill pipe and at the other terminal to ground, that is at the battery 22. Thus the first movement of the crank 73 will open the switch, disconnecting the signal generator from the drill pipe. From an exact mechanical viewpoint it is noted that the connection 100 is made through the grounding spring 78, Figure 12A, on to the metal housing 9, which in turn is connected to the drill pipe.

Shaft 41 is now rotating continuously, and hence when cam 66 moves to proper position pivoted arm 62 will move outwardly to disengage its shoulder 70 with the pawl 67. It will then rotate back to the position shown in Figure 12, closing switch 24 which has opened in the meantime, as previously explained. Thus by these operations switch 24 which is the intermittent switch, intermittently connects the generator to the drill pipe, and disconnects it therefrom. The relative length of the on and off periods can easily be adjusted by changing the relative positions of the high points on the cams 65 and 66. It will be noted that the continued rotation of shaft 41 keeps loading spring 68 to take up the unloading due to the step-by-step movement of the pawl 67.

Thus by means of the time control mechanism disclosed the operation of the switches for connecting and disconnecting the signal generator to and from the drill pipe is not initiated until about the time the device reaches the bottom of the bore hole. When the signal generator circuits are put into operation they are operated intermittently. Thus the life of the battery 22 is maintained at a maximum since it is not ever on a continuous short circuit. Trigger 55 must be reset manually since once it is operated by being released from the member 53, it remains in the position shown in Figure 11 to hold switch 23 closed. It will be apparent that the gears 39 and 40 may be relatively positioned with respect to each other on their threaded shafts so as to prearrange the relative times of arrival thereof at the ends of the threads on the shafts 41 and 42. Mechanical arrangements can easily be made to permit of the disengagement of gear 38 with the gears 39 and 40 to permit of this relative adjustment.

As those skilled in the art will clearly appreciate, the complete device includes the three units of Figures 1, 4 and 8 and a battery case or con-

7
tainer (not shown) below the unit shown in Figure 1, secured together in end to end relation in any suitable manner and enclosed within a suitable fluidtight housing (not shown) adapted to be lowered into a bore hole. For example, a length of pipe closed at the ends by threaded caps would be suitable to form a fluidtight housing for this purpose.

From the above description it will be apparent to those skilled in the art that the subject matter of this invention is capable of considerable variation, and I do not, therefore, desire to be strictly limited to the disclosure as given herein, but rather by the scope of the claims granted me.

15 What is claimed is:

1. In a device of the type described the combination comprising a housing, a vibrator motor mounted in said housing, means actuated by said motor for converting a direct current into an alternating current, a signal output circuit connected to said last means, a pair of switches connected in series in said circuit, a second vibrator motor intermittently operated by said first motor, and driving means actuated by said second motor for closing one of said switches after a predetermined time interval, and for intermittently actuating the other of said switches.

2. In the combination of claim 1, said driving means including a pair of threaded shafts and rotatable nuts mounted on said shafts, said nuts causing rotation of said shafts when they reach the ends of the threads thereof, said switches being respectively actuated by said shafts.

3. A signal transmitter comprising a signal current generator, a transmission circuit and means for intermittently connecting said generator to said transmission circuit comprising an electromagnetically operated ratchet energized from said generator, a pair of switches connected in series with said generator and said circuit, and means driven by said ratchet means for sequentially closing said switches and intermittently opening one of said switches.

4. In the combination of claim 3, said last means comprising an elongated gear driven by said ratchet means, a pair of rotatably mounted threaded shafts adjacent said gear, a pair of gears threadedly mounted on said shafts respectively and meshing with said elongated gear, spring biased means released by one of said shafts for closing one of said switches when said shaft is rotated, and means operated by the other of said shafts when it is rotated for intermittently closing the other of said switches, said threaded gears moving longitudinally of said shafts until they reach the end of the threads thereof whereupon continued rotation thereof causes rotation of said shafts.

WILLIAM R. FLATFORD.
